UNITED STATES PATENT OFFICE.

MARCELLUS J. SCANLAN, OF HERMOSA, SOUTH DAKOTA.

ANCHORING DEVICE.

Application filed May 27, 1924. Serial No. 716,174.

To all whom it may concern:

Be it known that I, MARCELLUS J. SCANLAN, a citizen of the United States, residing at Hermosa, in the county of Custer and 5 State of South Dakota, have invented certain new and useful Improvements in Anchoring Devices, of which the following is a specification.

This invention relates to anchoring devices 10 and more particularly to a ground anchor for anchoring a frame structure in an upright position upon the ground surface, and the invention has as one of its objects to provide an anchoring device which will be 15 substantial and durable and not liable to be pulled out of place when once driven into the ground.

Another object of the invention is to so 20 construct the anchor that a yoke member which is employed in combination therewith will be securely held connected with the anchor when engaged therewith, the yoke being designed to be secured to the frame structure or the like to be secured by the 25 anchor.

In the accompanying drawings:

Figure 1 is a perspective view illustrating 30 the manner in which the anchoring devices embodying the present invention are to be employed.

Figure 2 is a side elevation of the ground anchor;

Figure 3 is a front elevation of the said anchor;

Figure 4 is a fragmentary perspective 35 view illustrating the manner in which the anchor is connected with a companion member upon the frame structure.

Figure 1 of the drawings illustrates a 40 frame structure, which is to be secured by the anchor and which is indicated in general by the numeral 1, and comprises end stiles 2, a pair of intermediate stiles 3, and a plurality of rails indicated by the numeral 4, 45 the rails being secured by nails, screws, or other fastening devices, to the said stiles 2 and 3 and the said stiles 3 being positioned in parallelism and relatively close together. The stiles 2 and 3 may be of any desired 50 height and the rails 4 of any desired length but in any event the lower ends of the stiles 2 and 3 are all located in the same horizontal plane, so that the frame structure may be stood in an upright position upon the ground surface with the lower ends of all of the stiles engaging squarely with said surface.

The numeral 5 indicates in general a yoke with which the anchor of the structure is to cooperate in supporting the structure in upright position, and this yoke comprises 60 diverging arms 6 and a connecting bight portion 7. The yoke may be formed from a length of bar metal and the arms 6 thereof are preferably flat and of the initial dimensions of the material employed, the bight 7 65 being produced by reducing the intermediate portion of the material, or, in other words, that portion between the arms 6, to circular form in cross section. The arms 6 are bolted or otherwise secured, as at 8, to the lower 70 end portions of the stiles 3 so that the bight 7, which is of substantially semi-circular form, will extend between the said stiles, the said bight curving downwardly.

The anchor heretofore referred to, and 75 which is employed in combination with the yoke, is indicated in general by the numeral 9 and the said anchor is preferably formed from a single length of bar metal which at one end is brought to an entering point indicated by the numeral 10. Above the entering point and at different elevations, diagonal incisions 11 are formed in the lateral margins of the bar comprising the anchor 9, and the material beyond these incisions is 80 bent laterally from the plane of the bar and approximately at right angles to said plane to provide anchoring spurs indicated by the numeral 12. The spurs are so formed as to project in opposite directions from the bar 85 as clearly shown in Figure 2 of the drawings and when the bar is driven into the ground, these spurs will become embedded in the ground and will offer resistance to withdrawal of the anchor. Near its upper end 90 the bar comprising the anchor 9 has a lug 13 struck out therefrom so as to project at right angles laterally from one face of the said bar and this lug serves a purpose to be presently explained. Above the lug 13 the 95 bar is formed with an opening 14, and the numeral 15 indicates a hook having two bills 16 and a connecting shank portion 17 which is freely pivotally received within the opening 14, the hook being in this manner mounted upon the bar so that its spaced bills 16 will straddle the bar and be located at opposite sides thereof. The extremities of the bills of the hook 15 are presented in a general 100 downward direction when the hook is properly positioned for coaction with the bight 7 of the yoke 5, and by reference to Figure 110

4 of the drawings it will be observed that the anchor 9 is to be driven into the ground until its upper end projects but slightly above the ground surface, the hook 15 being 5 engaged with the said bights 7 at a suitable period in the operation of driving the anchor into the ground, and the driving operation being continued after this period until the bills of the hook have tightly engaged 10 over the bight 7. At this time the extremities of the hook bills will substantially engage or slightly enter the ground surface as clearly shown in Figure 4, and it will be evident that the frame structure will be securely anchored at its intermediate portion. 15 It will be evident that due to the provision of the lug 13, there is no likelihood of the anchor becoming loosened through any edge-wise play of the bar comprising the anchor, 20 inasmuch as such play is prevented by the resistance offered by the lug, the lug, being as previously stated, disposed in a plane substantially at right angles to the plane of the bar comprising the anchor and being embedded 25 in the ground. In consequence of the provision of the spurs 12 and lug 13, there is present in the anchor structure, means for preventing upward withdrawal 30 of the anchor, and likewise preventing its edgewise movement in the ground.

In order that the upper portion of the frame structure may be braced and the structure held in an upright position, there is provided a brace member which is best 35 shown in Figure 1 of the drawings and is indicated by the numeral 18. The said brace member comprises a bar of wood indicated by the numeral 19 which has its lower end cut to provide a ground engaging edge portion 20 and an edge portion 21 which is disposed at such an angle as to extend vertically when the brace is properly assembled with the frame structure. The upper end of the bar 19 is secured between the upper 40 ends of the stiles 3 in any suitable manner. 45

A yoke 25 corresponding to the yoke

5 heretofore described is secured to the lower end portion of the brace bar 19 with its bight extending rearwardly from the end of the said bar, and one of the anchors 50 shown in Figures 2 and 3 of the drawings, is driven into the ground within the yoke and until the hooks of the anchor engage over the bight of the said yoke.

Having thus described the invention, what is claimed as new is:

1. A ground anchor comprising a bar having an entering lower end, and provided with an opening near its upper end, and an anchoring hook comprising spaced hook members and a connecting portion extending between the inner ends of the same and fitting pivotally in the said opening, said hook members having bills curved toward the connecting portion of the hook and lying at opposite sides of the bar, the hook, between its connecting portion and the bills of the hook members, being of less length than the distance between the opening in the bar and the upper end of the bar.

2. A ground anchor comprising a bar having an entering lower end, and provided with an opening near its upper end, an anchoring hook comprising spaced hook members and a connecting portion extending between the inner ends of the same and fitting pivotally in the said opening, said hook members having bills curved toward the connecting portion of the hook and lying at opposite sides of the bar, the hook, between its connecting portion and the bills of the hook members, being of less length than the distance between the opening in the bar and the upper end of the bar, and an attaching member having terminal attaching portions and an intermediate bight portion, the bight portion being engaged in the bills of the hook members and against one vertical edge of said bar.

In testimony whereof I affix my signature.

MARCELLUS J. SCANLAN. [I. S.]
